UNITED STATES PATENT OFFICE

168,082

SOFA BED

Forest Wilson, Chicago, Ill.

Application November 21, 1950, Serial No. 13,083

Term of patent 3½ years

(Cl. D15—11)

To all whom it may concern:

Be it known that I, Forest Wilson, a citizen of the United States, residing at Chicago, county of Cook, and State of Illinois, have invented a new, original, and ornamental Design for a Sofa Bed, of which the following is a specification, reference being had to the accompanying drawing, forming a part thereof, in which:

Figure 1 is a perspective view of a sofa bed, embodying my new design, shown in the position for daytime use; Fig. 2, a perspective view of the sofa bed embodying my design, in the position for night use as a bed; Fig. 3, a plan view of a sofa bed embodying my design in position for daytime use; Fig. 4, a front elevational view of the sofa bed shown in Fig. 1; Fig. 5, a rear elevational view of the sofa bed shown in Fig. 1, and Fig. 6, a side elevational view of the sofa bed of Fig. 1.

I claim:

The ornamental design for a sofa bed, as shown.

FOREST WILSON.
